(74) Attorney, Agent, or Firm — **MALLOY & MALLOY, P.L.**

(57) **CLAIM**

The ornamental design for infant garment, as shown and described.

DESCRIPTION

FIG. 1 is a front elevation view illustrating our design for infant garment;

FIG. 2 is a right side view thereof;

FIG. 3 is a rear elevation view thereof;

FIG. 4 is a rear elevation view in an open orientation thereof;

FIG. 5 is a left side view in an open orientation thereof; and,

FIG. 6 is a rear perspective view taken from FIG. 4 thereof. The broken lines shown illustrate portions of the infant garment that form no part of the claimed design.

1 Claim, 6 Drawing Sheets
